LOCK

Harold Machinist, San Quentin, Calif., assignor
of one-tenth to Margaret Slater, Berkeley,
Calif.

Application February 13, 1933, Serial No. 656,609

7 Claims. (Cl. 70—47)

This invention relates to improvements in locks and has for its principal object, the provision of a safe and secure lock mechanism designed to be opened by a key, but only by the one authorized to use such key.

A further object is to equip the lock with simple and unique means to forestall any tampering with the mechanism, by unauthorized persons.

10 An additional object is to produce a lock that is exceedingly simple in construction, economical to manufacture, highly efficient in use, and which lock simulates the appearance of an ordinary lock.

15 Other objects and advantages will be apparent during the course of the following description.

In the accompanying drawings forming a part of this specification and in which like numerals 20 are employed to designate like parts throughout the same,

Fig. 1 is a front elevation of a lock having my invention incorporated therein,

25 Fig. 2 is an enlarged detail cross sectional view on the line 2—2 of Fig. 1,

Fig. 3 is a side elevation of a lock cylinder having my invention applied thereto and partly broken away in order to illustrate the mechanism thereof,

30 Fig. 4 is a cross sectional view on the line 4—4 of Fig. 3 and showing the parts in locked position,

Fig. 5 is a view similar to Fig. 4 showing the first pusher pin and locking pin in picked position,

35 Fig. 6 is an end elevation of one of the rings, Fig. 7 is a side elevation of the rings removed from the cylinder,

40 Fig. 8 is a side elevation of the cylinder with one ring positioned thereon,

Fig. 9 is an enlarged top plan view of the cylinder and rings in assembled position,

45 Fig. 10 is a cross sectional view taken on the line 12—12 of Fig. 11,

Fig. 11 is a side elevation of Fig. 1, showing a portion thereof broken away and showing the pusher pins in the position they will assume when keyed in actuation, and

50 Fig. 12 is a view similar to Fig. 10, taken on the line 12—12 of Fig. 11 and showing the key actuation of the lock.

In the accompanying drawings wherein for the purpose of illustration is shown a preferred embodiment of my invention, the numeral 5 designates the barrel of a lock having a cylinder 6 capable of rotating within the barrel. The cylinder has the customary key-way 7 and the customary push pins 8, 9, 11, 12 and 13. These push pins 8 to 13 inclusive are contacted by locking pins 14, 16, 17, 18 and 19, respectively. These locking pins 14, 16, 17, 18 and 19 are in turn pressed downwardly against the push pins by springs 21, 22, 23, 24 and 26, respectively. The construction thus far described is common in 10 this type of lock.

5 My improvement consists in placing about the cylinder 6, a series of peculiarly formed bands 27, 28, 29, 31 and 32. Referring now to Figs. 6, 7 and 8, particularly, it will be noted that the ring 32 has a portion thereof cut away so as to form shoulders 33 and 34 (see Fig. 6). This ring 32 is pinned to the cylinder as by a pin 36. The ring 29 is cut away on opposite sides thereof so as to form shoulders 37 upon one side, which engage either the shoulders 33 and 34 of the ring 31. This ring 29 is further cut away on its opposite side so as to provide shoulders 38 which corresponds to the shoulders 33 and 34 of the ring 31. The ring 28 is likewise cut so as to form shoulders 39 and 41. The ring 27 is cut so as to form shoulders 42. The cutting of these rings is such as to leave a space between the adjacent faces of the shoulders of the adjacent rings. These spaces are best shown at A and B (see Fig. 4), also (see Fig. 3). This arrangement permits a slight rotary play between the various rings. Each ring is provided with an opening 43 through which the locking pins may pass (see Figs. 4 and 5).

30 The operation of my device is as follows:—

Assuming that a key is employed for actuating the lock, the key is inserted in the customary manner which will result in elevating the pusher pins 8, 9, 11, 12 and 13, thus lifting them to the position shown in Figs. 11 and 12, at which time the upper ends of all of the pusher pins will be extending into the openings 43 in the rings 27, 28, 29, 31 and 32, respectively and will be flush with the outer surface of the rings. At this time the cylinder with the rings thereon may be rotated so as to actuate the bolt mechanism. Now assume that a person attempts to pick the lock, without employing a key. In picking a lock it is customary to place rotary tension on the cylinder and to then with a pick press upwardly on the bottom of each of the pusher pins. We will now assume that, as a matter of illustration, the person pushes upwardly upon the pin 13 and moves the locking pin 19 to the position of Fig. 5. The rotary tension 50

55 55

will now cause a binding action upon the remaining locking pins. The person now pushes upwardly upon the various pusher pins in accordance with standard practice. As soon as the pusher pin, for instance 12, pushes the locking pin 18 upwardly until it reaches the position of Fig. 12, then a slight movement will occur, which will offset the pusher pin from the locking pin. As a consequence the locking pin will not be raised any further, nor will the pusher pin be raised further. As a result a person attempting to raise any one of the pusher pins will automatically cause the locking pin to be disengaged as far as movement is concerned, from its pusher pin with the result that the lock cannot be actuated without the use of a key.

It is to be understood that the form of my invention herewith shown and described is to be taken as a preferred example of the same and that various changes relative to the material, size, shape and arrangement of parts may be resorted to without departing from the spirit of the invention within the scope of the subjoined claims.

Having thus described my invention, I claim:

1. In a lock having a cylinder and a barrel, a plurality of rings positioned on said barrel, said rings interlocking one with the other, means for securing one of said rings to said cylinder, said rings having openings formed therethrough whereby the locking pins may extend between said barrel and said cylinder.

2. In a locking mechanism, a barrel, a rotatable cylinder positioned in said barrel, a plurality of rings mounted on said cylinder, one of said rings being secured to said cylinder, a shoulder formed on each of said rings and adapted to engage a shoulder formed on the next adjacent ring, each of said rings having an opening formed therethrough whereby locking pins may extend from said barrel to said cylinder.

3. In a locking mechanism, a barrel, a rotatable cylinder positioned in said barrel, a plurality of rings mounted on said cylinder and serving to space said cylinder with respect to said barrel, one of said rings being secured to said cylinder, shoulders formed on each of said rings, the shoulders of one ring being adapted to engage the shoulders of the next adjacent ring when said cylinder is rotated, the abutment of each succeeding ring shoulders taking place pro-

gressively as the cylinder is rotated, each of said rings having an opening formed therethrough whereby locking pins may extend from said barrel to said cylinder.

4. In a lock of the class described, having a barrel and a cylinder rotatable therein, a plurality of rings mounted on said cylinder, said rings having openings formed therethrough whereby locking pins may pass from said barrel into said cylinder, said rings being arranged in juxtaposed relation and having offset mating shoulders, one of said rings being secured to said cylinder and adapted to limit the rotational movement of the remaining rings relative to said cylinder.

5. In a lock of the class described, having a barrel and a cylinder rotatable therein, locking pins and pusher pins mounted therein, means entirely encompassing said cylinder and having locking pin openings formed therethrough, said means embodying a plurality of shouldered rings adapted for interlocking relation, one of which is fixed to said cylinder, whereby when the cylinder is held under tension in picking the lock the pusher pins are caused to offset relative to the locking pins to prevent the raising of said locking pins.

6. In a lock of the class described having a barrel and a cylinder rotatable therein, locking pins and pusher pins mounted therein, means entirely encompassing said cylinder and having locking pin openings formed therethrough, said means embodying a plurality of mating shouldered rings adapted for slight rotational movement relative to each other, one of said rings being pinned to said cylinder and adapted to limit the rotational movement of the remaining rings and the cylinder to cause the offsetting of the pusher pins relative to the locking pins.

7. In a lock of the class described, having a barrel and a cylinder rotatable therein, locking pins and pusher pins mounted therein, means entirely encompassing said cylinder and having locking pin openings formed therein, said means embodying a plurality of interlocking rings, and said rings adapted to limit the rotational movement of said cylinder and cause the offsetting of the pusher pins relative to the locking pins to prevent picking of said lock.

HAROLD MACHINIST
